UNITED STATES PATENT OFFICE.

ALBERT E. EVANS, OF PITTSBURGH, PENNSYLVANIA, ASSIGNOR TO PITTSBURGH PLATE GLASS COMPANY, A CORPORATION OF PENNSYLVANIA.

APPARATUS FOR MAKING PLATE GLASS.

Application filed June 5, 1924. Serial No. 718,037.

To all whom it may concern:

Be it known that I, ALBERT E. EVANS, a citizen of the United States, and a resident of Pittsburgh, in the county of Allegheny and State of Pennsylvania, have made a new and useful invention in Improvements in an Apparatus for Making Plate Glass, of which the following is a specification.

The invention relates to apparatus for making plate glass and particularly to the means for handling the glass pots between their removal from the usual melting and fining furnace, and the pouring of the glass upon the casting table and for regulating their temperature. It has for its principal objects, the provision of a tunnel furnace and car handling construction, having improved means, (1) for securing in an economical way, the necessary temperature conditions and for regulating such temperatures; (2) for securing the movement of the cars carrying the pots into, through and out of the furnace; and (3) for protecting the cars carrying the pots and the moving means therefor against rapid deterioration incident to the high temperature conditions in the furnace. One embodiment of the invention is illustrated in the accompanying drawings wherein:

Figure 1 is a diagrammatic plan view of the apparatus. Fig. 2 is a side elevation thereof. Fig. 3 is a longitudinal vertical section through the furnace. Fig. 4 is a longitudinal horizontal section on the line IV-IV of Fig. 5. Fig. 5 is a transverse section on the line V-V of Fig. 3. Fig. 6 is an end elevation of the furnace. Fig. 7 is a vertical longitudinal section through two adjoining cars, the one at the left being about to leave the furnace. Fig. 8 is a section through a car which is about to enter, and Fig. 9 is a view in elevation of the right end of the car about to leave the furnace, parts of the furnace being in section.

The furnace or leer is of the tunnel type and is designed to be used in connection with the usual furnace employed for heating and fining plate glass in pots preliminary to casting it into sheets upon the regulation type of casting table. In the accepted practice of the art, the pots are removed from the melting furnace by means of a crane, after which they are transported to the vicinity of the casting table and seated upon a base or "turtle". At this point the crane is disengaged

and the cold glass upon the surface of the bath in the pot is skimmed, the pot is engaged by a "teeming crane" and is carried to the casting table where it is teemed or poured across one end of such table by tilting the pot. The period of time required between the removal of the pot from the melting furnace and the pouring operation necessitates the skimming of the pot in all instances because of the cold skin which is formed at the surface, and as this period of time varies, it is difficult to have the glass always at the proper temperature for pouring when the glass reaches this stage of the operation. The present device is designed to avoid these difficulties by providing a secondary furnace adjacent the casting table in which the pots are placed as they are brought from the melting furnace, and in which the glass in the pots can be brought to a definite and uniform temperature preliminary to pouring, thus giving a consistency at pouring which is the proper one and always the same, and avoiding the necessity of skimming the pot preliminary to casting. The avoidance of skimming involves a saving of glass and a reduction of labor.

Briefly stated, the secondary furnace is in the form of a tunnel kiln or leer through which a track passes for cars upon which the pots are mounted, the furnace being of a capacity such as to hold upwards of five or six cars at one time. The pots are removed from the melting furnace in the usual way and placed upon the cars which are then moved along the track and into the furnace. They are then moved step by step through the furnace and during this movement, the glass in the pots is brought to the proper temperature for pouring. As a car is moved into the entrance end of the furnace, the car at the exit end of the furnace is moved out and onto the turn-table, this being preferably accomplished in one movement. The turn-table takes the place of the "turtle" heretofore referred to and the pot is lifted from the car on this turn-table by the teeming crane and moved to the casting table and poured in the usual way. Since the secondary furnace is located adjacent the casting table, the period of time elapsing between the removal of the pot from the furnace and the pouring of the glass is relatively short, so that no skimming is required, and the glass is poured at the temperature which is

found to be most suitable. The use of the turn-table is desirable as it acts as a switch for returning the cars for re-use, and furthermore, serves to permit the turning of the 5 pot to a position in which it can best be engaged by the tongs of the teeming crane, this being primarily a consideration where pots are used of oval cross section as opposed to pots having a circular cross section.

10 Referring first to the general arrangement as shown in Figs. 1 and 2, 1 is the tunnel furnace through which the cars 2, 3, 4, 5, etc. are passed; 6 is a section of track leading from one or more pot furnaces of the usual 15 type (not shown); 7 is a straight section of track leading through the furnace to the turn-table 8; 9 is a return section of track for bringing the empty cars back to the section 6; 10 is the casting table, the corner 20 only of which is shown; 11 is a pusher bar mounted for reciprocation and adapted on its forward movement to engage the car 2 and move it into the furnace and at the same 25 time to engage the car 4 adjacent the outlet end of the furnace and move it onto the turn-table 8; and 12 is the motor operating through suitable reduction gearing for operating the pusher bar 11.

30 The construction of the tunnel furnace will be readily understood by reference to Figs. 3 to 6. At each end of this furnace is a door 13 mounted for vertical movement and designed to be in closed position except when a car is being moved into the furnace and another one is being moved out. These 35 doors are operated by means of chains or cables 14 passing over pulleys 15 and operated from air cylinders 16. The furnace has an arch 17 as indicated in Fig. 5 and is divided into a plurality of compartments (one for each pot) by the transverse partitions 18 (Fig. 3) so that the different sections may be given different temperatures, the method of operation being to gradually 40 increase the temperature of the glass as the pot progresses through the furnace.

45 Gas is supplied for heating the various compartments by means of the burners 19 (Fig. 5) projecting through the wall of the furnace at one side thereof. The air necessary for giving combustion is supplied through the vertical flues 20, and the gases of combustion flow upwardly and over the tops of the pots as indicated by the arrows 50 in Fig. 5, a large part of the heat for the glass being provided by the reflection from the arch 17. The gases of combustion, after passing through the furnace, enter the downwardly directed flues 21 and after passing 55 through the recuperative checker work, escape past the damper 22 to the stack tunnel 23.

60 The recuperative portion of the furnace extends longitudinally thereof and may be 65 constructed in various ways. As illustrated,

the passageways for the gases from the outlet flues 21 consist of the hollow tiles 24 having the passages 25, 26 and 27 therethrough (Figs. 3 and 5), so that the gases from the flues 21 first pass through the passages 25 to the passages 26 and thence to the 70 passages 27 leading to the stack. Air to the inlet flue 20 is supplied from the chambers 28 past the dampers 29 to the passages 30. From this point, it circulates up past the tiles 24 through the passages 31 to the 75 passages 32, which communicate with the lower ends of the vertical flues 20, the air for combustion purposes being in this manner heated to a relatively high temperature preparatory to mixing with the gas from the 80 burners 19.

85 The cars which carry the pots preferably each consist of a metal framework 33 (Figs. 7 and 8) carried by wheels 33^a and provided with tops 34 of refractory material such as clay. These blocks project laterally into proximity with the side walls of the furnace, as indicated at 35 in Fig. 9, which 90 feature in connection with the laterally projecting blocks 36, serve to partition off the upper portion of the furnace from the portion below the car tops, thus tending to protect the metal parts of the car from the high temperatures which necessarily exist 95 in the upper portion of the furnace. The blocks 34 on the succeeding cars also abut and interfit as indicated at 37 (Fig. 7), so that a continuous refractory wall is provided tending to prevent the passage of heat 100 from the upper portion of the furnace to the lower portion. Additional protection to the metal work of the cars is also afforded by the use of the series of pipes 38 extending along each side of the furnace beneath the 105 blocks 36, cooling fluid such as water, being circulated through these pipes from the 110 headers 39 at the ends thereof (Fig. 4).

110 The cars are moved through the furnace step by step by means of the pusher bar 11 built up of plates and channel bars as indicated in the cross section shown in Fig. 9. This pusher bar and its supporting and operating means are mounted in a passageway 115 extending longitudinally of the furnace and opening upwardly through the bottom thereof. The support of the pusher bar is provided by means of the series of rollers 41 carried by suitable standards 42 located at intervals along the length of the passageway. On the under side of the bar 11 is a rack bar 42^a, and this rack bar is operated by means of the pinion 43 located in the passageway adjacent the entrance end of the furnace as indicated in Fig. 4 and mounted upon a transverse shaft 44. The shaft is operated from the motor 12 through the intermediary of the reduction gearing 45 and a worm gear and worm in the casing 46. The pusher bar is provided with a pair of 120 125 130

pivoted dogs 47 and 48 normally occupying the positions indicated in Figs. 7 and 8 by reason of the portions 49 and 50, which are heavy enough to counterbalance the portions 5 in advance of the pivots. Each of the cars is provided with a downwardly projecting part 51 adapted to be engaged by the dogs. The dogs are spaced apart on the pusher bar a distance such that when the dog 48 engages the car 2 (see Fig. 2), the dog 47 will engage the car 4 at the outlet end of the furnace. The spacing is also such, that when the pusher bar is moved ahead so as to carry the car 2 into the furnace so that it 10 occupies the position of the car 3, the car 4 at the outlet end of the furnace will be brought to the position of the car 5 on the turn-table 8. A single movement of the pusher bar, therefore, brings a new car into 15 the furnace, moves the car at the outlet end of the furnace out of the furnace and onto the turn-table 8, and moves each of the other cars in the furnace ahead one car length. This reduces the time and labor incident to 20 handling the cars to a minimum, the pot upon the car 5 now being in position to be engaged by the teeming crane, and the car 5 itself being in position to be returned on the track 9 to the track 6.

30 In order to protect the metal work in the passageway 40 from the heat of the furnace, a plurality of conduits 52 are employed connected to suitable headers 53 at the ends of the passageway and a cooling fluid such as 35 water is circulated through these conduits. In order to secure a uniform cooling along the length of this passageway and along the sides of the furnace by the conduits 38, a part of the fluid in each set of pipes is pref- 40 erably supplied from each end thereof, so that the flow in alternate pipes is in different directions.

In operation, the pots are supplied to the entrance end of the furnace at periods corresponding to the casting periods, that is, every seven or eight minutes, so that with a six pot furnace, the pots are in the furnace about 40 minutes. During this time, they are raised in temperature about 200 degrees 50 and the molten glass in the pots has a temperature of approximately 2100 degrees when the pots are removed from the furnace. As the glass is cast immediately, no skimming is required and the glass as it reaches 55 the casting table is at a temperature and degree of fluidity most suitable for this stage of the operation. The use of the apparatus also increases the capacity of the melting furnace as the period of hold-over 60 which is required in the melting furnace is reduced by the period of time which the pots occupy while in the secondary furnace.

What I claim is:

1. In combination in apparatus for han- 65 dling and treating pots containing molten

glass preliminary to casting the glass into plates, which comprises, a tunnel furnace having a track therethrough, a series of cars on the track for carrying the pots, a moving device for the cars extending longitudinally 70 of the furnace, engaging means on such device adapted to engage the car next to the outlet end of the furnace and also a car located outside the entrance end of the furnace, but adjacent thereto, and means for reciprocating said device so that on the forward movement thereof, said car next the outlet end of the furnace is moved outside of and away from the furnace and said car adjacent the entrance is moved into the furnace, 75 thereby moving all of the other cars in the furnace ahead one car length.

2. In combination in apparatus for han- 80 dling and treating pots containing molten glass preliminary to casting the glass into plates, which comprises, a tunnel furnace having a track therethrough, a series of cars on the track for carrying the pots, a turn-table for the cars to which the track ex- 85 tends from the outlet end of the furnace, a pusher device extending longitudinally of the furnace and provided with a pair of engaging devices arranged so as to engage re- 90 spectively the car in the furnace next to the outlet end thereof and a car outside the 95 furnace, but adjacent the inlet end thereof, and means for giving the pusher device a forward movement such that it will move said car adjacent the outlet end of the furnace, out of the furnace and onto the turn- 100 table, and at the same time move said car adjacent the inlet end of the furnace into the furnace, thereby moving all of the other cars in the furnace ahead one car length.

3. In combination in apparatus for han- 105 dling and treating pots containing molten glass preliminary to casting the glass into plates, which comprises, a tunnel furnace having a track therethrough, a series of cars on the track for carrying the pots, a moving device for the cars extending longitudinally 110 of the furnace, engaging means on such device adapted to engage the car next to the outlet end of the furnace and also a car located outside the entrance end of the furnace, but adjacent thereto, and means for reciprocating said device so that on the forward movement thereof said car next the outlet end of the furnace is moved outside of and away from the furnace and said car adjacent the entrance is moved into the furnace, thereby moving all of the other cars in the furnace ahead one car length, said 115 engaging means comprising pivoted dogs adapted to swing to inoperative position during the backward movement of said moving device.

4. In combination in apparatus for han- 120 dling and treating pots containing molten glass preliminary to casting the glass into 125

plates, which comprises, a tunnel furnace having a track therethrough, a series of cars on the track for carrying the pots, a turntable for the cars to which the track extends from the outlet end of the furnace, a pusher device extending longitudinally of the furnace and provided with a pair of engaging devices arranged so as to engage respectively the car in the furnace next to the outlet end thereof and a car outside the furnace but adjacent the inlet end thereof, and means for giving the pusher device a forward movement such that it will move said car, adjacent the outlet end of the furnace, out of the furnace and onto the turntable, and at the same time move said car adjacent the inlet end of the furnace into the furnace, thereby moving all of the other cars in the furnace ahead one car length, said engaging devices comprising pivoted dogs adapted to swing to inoperative position during the backward movement of said moving device.

5. In combination in apparatus for handling and treating pots containing molten glass preliminary to casting the glass into plates, which comprises, a tunnel furnace having a track therethrough, a series of cars on the track for carrying the pots, a rack bar extending longitudinally of the furnace beneath the cars and guided for endwise sliding movement, a pinion engaging the rack bar, means for rotating the pinion back and forth to reciprocate the rack bar, and a

pair of pivoted dogs on the bar, arranged so that when the bar is in retracted position, the forward dog will engage the car in the furnace next the outlet end thereof, while the other dog will engage a car outside the entrance end of the furnace, but adjacent thereto, so that on the forward movement of the rack bar said car at the outlet end of the furnace will be moved out of and away from the end of the furnace, while said car outside the entrance end of the furnace will be moved into the furnace thereby moving all of the other cars in the furnace ahead one car length.

6. In combination in apparatus for handling and treating pots containing molten glass preliminary to casting the glass into plates, which comprises, a tunnel furnace having a track therethrough and a passageway longitudinally of its bottom opening upwardly, a series of cars on the track for carrying the pots, a moving device for the cars extending longitudinally of the passageway, means extending upwardly from said device for engaging the cars, conduit means also extending longitudinally of the passageway, and means for circulating a cooling fluid through said conduit means.

In testimony whereof, I have hereunto subscribed my name this 2nd day of June, 1924.

ALBERT E. EVA VS.
